UNITED STATES PATENT OFFICE

2,552,203

VOLTAGE DOUBLER MAGNETIC AMPLIFIER

Raymond E. Morgan, Scotia, N. Y., assignor to
General Electric Company, a corporation of
New York

Application April 2, 1948, Serial No. 18,603

3 Claims. (Cl. 321—24)

1

My invention relates to saturable reactor magnetic amplifiers for amplifying small direct currents, and in particular to an improved regenerative magnetic amplifier, which provides an amplified D.-C. output signal which corresponds, in a substantially linear manner within the normal operating range of the amplifier, to the magnitude of a relatively feeble D.-C. input signal.

It is an object of my invention to provide an improved magnetic amplifier which will be responsive to extremely feeble direct current input signals.

It is another object of my invention to provide an improved magnetic amplifier in which the gain has been greatly increased without increasing the speed of response.

It is another object of my invention to provide an improved high sensitivity magnetic amplifier, the operation of which is not affected by the earth's magnetic field.

It is a further object of my invention to provide an improved magnetic amplifier of the type described adapted for use with either high impedance or low impedance input signal circuits, which will not introduce undesirable voltages or currents into the input signal circuit.

The features of my invention which I believe to be novel and patentable are pointed out in the claims appended hereto. For a better understanding of my invention, reference is made in the following description to the accompanying drawing in which Fig. 1 is a schematic diagram illustrating a preferred embodiment of my invention, and Fig. 2 is an equivalent circuit which will be used in explaining the operation of Fig. 1.

Referring now to Fig. 1, alternating current input terminals 1 may be connected to a source of alternating current, such as a commercial 60 cycle electric outlet or an oscillator for producing alternating current of a higher frequency. A saturable magnetic core has a center leg 2 split lengthwise to divide the core into two similar sections 3 and 4, separated by a small air gap 5 which is preferably about $\frac{1}{2}$ inch to $\frac{1}{8}$ inch wide for reasons which are hereinafter explained. Each section has two legs, an outer leg and one-half the center leg of the reactor, which preferably are of approximately equal cross-sectional

area, so that flux densities are equal in both legs of each section. Saturable magnetic core sections 3 and 4 have reactor windings 6 and 7 respectively wound thereon. Signal windings 8 and 9 are wound about both sections of the center leg 2. For many purposes, it is convenient to have two signal windings as shown, so that a bias signal can be applied to one winding and a varying signal to the other; or so that two signals can be applied to the two windings respectively to obtain an output proportional to the sum or the difference between the two. However, for many purposes one signal winding will be sufficient, and for other purposes more than two such windings will be necessary. The number of signal windings which may be placed on the center leg in the manner shown is limited only by the space available. A short-circuited winding 10 is also wound about both sections of the center leg. 10

20 The purpose of this winding is discussed hereinafter.

Rectifiers 11 and 12 and capacitors 13 and 14 are connected, as shown, to form two similar circuits connected in parallel to terminals 1, each 25 of said circuits comprising a rectifier, a reactor winding, and a capacitor connected in series. The order of the elements is preferably that shown, but may be changed without greatly 30 affecting the operation of the amplifier, provided only that the capacitors must remain at one end and be connected together. For example, the rectifiers may be connected in the circuit between the reactor windings and the capacitors. Output connections are provided to connect a load 35 15 across the two capacitors as shown.

Fig. 2 is an equivalent circuit of that portion 40 of the circuit of Fig. 1 traversed by the alternating current supplied at terminals 1. Windings 6 and 7 are shown as variable inductors, since the incremental or effective inductance of these windings changes as the magnetic core upon which they are wound saturates. It is evident that the circuit of Fig. 2 is essentially a voltage doubler circuit in which, if the impedance of inductors 6 and 7 is small, there is a D.-C. voltage 45 across load 15 approximately equal to twice the A.-C. voltage at terminals 1. If the impedance of inductors 6 and 7 is increased, a greater portion 50 of the available voltage appears as a voltage

drop across these inductors, and the voltage across load 15 is reduced. Conversely, if the impedance of inductors 6 and 7 is decreased, the voltage across load 15 is increased.

Again referring to Fig. 1, the polarities of rectifiers 11 and 12 are such that current flows through winding 6 during one half of each alternating current cycle and flows through winding 7 during the opposite half cycle. Thus, the current through winding 6 has a D.-C. component which produces a unidirectional magnetic flux flowing counterclockwise through magnetic core section 3, and the D.-C. component of current flowing through winding 7 produces a unidirectional magnetic flux which flows clockwise through magnetic core section 4. These two fluxes both pass through signal windings 8 and 9 in an upward direction and hence are of mutually additive polarity as they pass through these windings.

The unidirectional fluxes tend to partially saturate the saturable magnetic core sections 3 and 4. Now if a direct current is passed through the signal windings 8 or 9, this current also produces a unidirectional flux which is either additive or subtractive to the fluxes produced by windings 6 and 7, depending upon the direction of current flow through the signal windings. If the flux produced by current flowing in the signal windings is of the additive polarity, the degree of saturation of the magnetic core is increased, but if this flux is of the subtractive polarity, the degree of such saturation is decreased. Since the effective inductances of windings 6 and 7 vary inversely with saturation of the magnetic core, currents through the signal windings produce changes in the impedance of the reactor windings, and hence changes in the voltage across load 15. Within the normal operating range of the amplifier, changes in voltage across the load correspond in a substantially linear manner to the much smaller changes in current through the signal windings. This circuit is regenerative because any increase in saturation of the magnetic core, which reduces the effective inductance of the reactor windings, causes larger direct currents to flow through the reactor windings, which in turn further increases the degree of saturation of the magnetic core. This regenerative effect makes it possible to secure a relatively high gain with this type circuit.

It should be noted that in addition to the D.-C. component of current flowing through reactor windings 6 and 7, there are also A.-C. components which produce alternating fluxes in the magnetic core. Since current flows through windings 6 and 7 respectively during opposite half cycles, the fundamental frequency components of alternating flux produced by these two windings are 180° out of phase. Hence, at any given instant the fundamental frequency flux produced by winding 6 flows through the signal windings in a direction opposite to that of the fundamental frequency flux produced by winding 7. These two fluxes are thus of mutually subtractive polarity as they flow through the signal windings, and consequently the voltages which they induce in the signal windings cancel out and have no effect upon the input circuits.

In high-sensitivity magnetic amplifiers previously used, it has frequently been necessary to surround the saturable reactor element with a magnetic shield, to prevent the earth's magnetic

field, or other external fields, influencing the saturation of the core. It will be noted that in my amplifier, every flux path has equal density in opposite directions, since the flux flows upward through one leg and downward through another leg of equal cross-sectional area, so that effects due to external fields cancel out and the earth's magnetic field has no effect upon the operation of the amplifier.

In the circuit which I have described, the gain of the amplifier can be greatly increased without affecting the time constant of the input windings, which largely determines the time of response of the amplifier, by utilizing the resonant effects obtainable by proper choice of the values of capacitors 13 and 14 in conjunction with the inductance of windings 6 and 7. These values of capacitance and inductance should be such that each winding and its associated capacitance is series resonant at a frequency somewhat below the frequency of the alternating current source connected to terminals 1.

Then as the magnetic core saturates and the inductance of windings 6 and 7 decreases, each of the two circuits connected in parallel to terminals 1 will approach resonance, and the voltage increase across load 15 will be much greater than it would be were it not for the resonant effect. The closer to resonance the circuits are tuned, the greater the gain which may be realized in this way; but when the circuits come too close to resonance, instability problems arise. Hence the preferable degree of tuning is a compromise value which must be chosen to fit the particular application, and the voltage and frequency stability of the alternating current source. With a commercial 60 cycle alternating current source and a voltage variation not exceeding $\pm 10\%$, I utilize resonant effects to secure a gain 10 times the maximum obtainable without resonance. If both voltage and frequency are held constant within $\pm 0.1\%$, I can secure good stability with my amplifier adjusted to give a power gain of one billion.

When the amplifier is used with a 60 cycle per second source of alternating current, the reactor windings and capacitors may be initially tuned to a frequency as low as 7 to 10 cycles per second; and still a considerable increase in gain is obtainable due to resonant effects, since the inductance of windings 6 and 7 may vary over quite a wide range as the magnetic core saturates.

When this amplifier is used to amplify very feeble input signals, it is necessary that center leg 2 be split lengthwise, as described, in order to eliminate the hysteresis effect which would otherwise mask the applied signal. If the core is not split, alternating components of flux produced by windings 6 and 7 tend to flow around the circumference of the magnetic core and not to flow through center leg 2 at all. This then leaves only unidirectional flux flowing through center leg 2. Because of hysteresis, a magnetic material does not return to a state of zero magnetism when the magnetizing force is removed. Hence there tends to be a residual magnetism which may be greater than the magnetization produced by a very feeble signal. I have found that with a non-split core, hysteresis limits the usable D.-C. signal applied to the signal windings to a minimum value of about 1 microwatt. By splitting the center leg lengthwise, a narrow air gap is provided which has a high re-

luctance and thus tends to prevent the flux following this circumferential path; so that alternating fluxes as well as unidirectional fluxes must flow through center leg 2. This insures that the magnetization of center leg 2 traverses a complete hysteresis loop each cycle of the alternating current, and so prevents residual magnetism from masking the signal. I have found that this split core construction may reduce hysteresis effects by a factor of over a million. With my circuit, including the split core, I have obtained good results with D.-C. applied signals as small as 1.0 micro-microwatt with an amplifier power gain of over one million.

The alternating flux through leg 2, however, will induce voltages in signal windings 8 and 9, unless the flux flowing through one section of leg 2 is exactly balanced by a flux 180° out of phase flowing through the other section of leg 2. If the signal windings are connected to high impedance circuits, and the signal windings have a large number of turns in order to obtain large gains and to make the amplifier responsive to very feeble signals, the voltages induced in the signal windings may be of the order of thousands of volts, which high voltages are dangerous to operating personnel and may cause the breakdown of the winding insulation. On the other hand, if the signal windings are connected to low impedance circuits, the induced voltages may cause circulating currents in the low impedance circuit which will very often be extremely undesirable. For example, if the signal circuit contains a thermocouple, circulating currents will cause internal heating of the thermocouple and thus produce an erroneous measurement of temperature. I have found that these difficulties are overcome by placing a short circuited winding 10 wound about both sections of center leg 2 as shown. The number of turns required in winding 10 depends upon the number of turns in the other windings and other constants of the circuit; and it may, for example, be a single turn, or may in other cases be 100 turns or more. This short circuited winding presents a high impedance to any net alternating flux flowing through center leg 2, so that a flux which flows through one section of the center leg must be exactly balanced by another flux, 180° out of phase with the first, flowing through the other section. I have found that this arrangement, together with an air gap of proper dimensions as herein described, substantially eliminates the difficulties heretofore mentioned due to induced voltages and circulating currents in the signal windings.

I have found that a preferable width for air gap 5 is in the order of $\frac{1}{2}$ inch to $\frac{1}{8}$ inch. In most cases a gap $\frac{1}{2}$ inch wide or greater is needed to prevent the objectionable hysteresis effects previously described. On the other hand, it is desirable that the gap be no larger than $\frac{1}{8}$ inch for the following reason: During a part of each A.-C. cycle, the flux density produced is very high. This high flux density, despite the action of short-circuited winding 10, tends to produce circulating currents in signal windings 8 and 9 and the circuits connected thereto. These currents, combined with the inductance of the signal windings, cause a phase shift of flux sufficient to cancel out small signals. That is, current circulates in the signal windings during that part of the cycle immediately after the rectifier has cut off current through the respective reactor windings, thus holding a flux that interferes with the signal. If

the air gap is about $\frac{1}{8}$ inch wide or less, some of this high density flux will cross the gap, and thus lower the flux density passing through center leg 2 sufficiently for short-circuited winding 10 to maintain balance between the fluxes in opposite sections of the leg.

In accordance with the provisions of the Patent Statutes, I have described the principle of my invention together with apparatus which I now consider to represent the best embodiment thereof; but I wish it to be understood that the apparatus described is illustrative only and that the invention can be carried out by other means.

What I claim as new and desire to secure by Letters Patent of the United States is:

1. A voltage-doubler magnetic amplifier comprising alternating current input conductors, a saturable magnetic core, at least one signal winding and two reactor windings on said core, connections forming two circuits connected in parallel to said input conductors, each such circuit comprising one of said reactor windings, a rectifier, and a capacitor connected together in series, said capacitors being at corresponding ends of such circuits and connected together, each such circuit being series resonant at a frequency lower than the alternating current frequency, said rectifiers having such polarities that said two circuits are respectively conductive during opposite half cycles of the alternating current, said windings being so disposed that fundamental frequency alternating components of magnetic flux respectively produced by currents through the two reactor windings pass through said signal winding with mutually subtractive polarities and unidirectional components of such flux pass through said signal winding with mutually additive polarities, and output connections for connecting a load across the two capacitors.

2. A voltage-doubler magnetic amplifier comprising alternating current input conductors, a saturable magnetic core having a center leg split lengthwise to divide said core into two substantially similar sections separated by an air gap approximately $\frac{1}{2}$ inch to $\frac{1}{8}$ inch wide, reactor windings on each of said two sections, at least one signal winding and a short-circuited winding each wound about both sections of the split center leg, connections forming two similar circuits connected in parallel to said input conductors, each such circuit comprising one of said reactor windings, a rectifier, and a capacitor connected together in series, said capacitors being at corresponding ends of such circuits and connected together, each such circuit being series resonant at a frequency lower than the alternating current frequency, said rectifiers having such polarities that said two circuits are respectively conductive during opposite half cycles of the alternating current, said windings being so disposed that fundamental frequency alternating components of magnetic flux respectively produced by currents through the two reactor windings pass through said signal winding with mutually subtractive polarities and unidirectional components of such flux pass through said signal winding with mutually additive polarities, and output connections for connecting a load across the two capacitors.

3. A voltage doubler magnetic amplifier comprising, alternating current input conductors, a saturable magnetic core, at least one signal winding and two reactor windings on said core, con-

nections forming two circuits connected in parallel across said input conductors, each circuit comprising one of said reactor windings, a rectifier, and a capacitor connected together in series, said capacitors being at corresponding ends of such circuits and connected together, each circuit being series resonant at a frequency lower than the alternating current frequency, said rectifiers having polarities such that said two circuits are respectively conductive during opposite half cycles of the alternating current, said windings being so disposed that unidirectional components of magnetic flux produced in said core by current through the two reactor windings have mutually additive polarity relative to the flux produced therein by a current in said signal

winding, and output connections for connecting a load across the two capacitors.
